UNITED STATES PATENT OFFICE.

CHARLES A. STATLER, OF CHICAGO, ILLINOIS.

ROOF.

1,372,208.

Specification of Letters Patent. Patented Mar. 22, 1921.

Original application filed March 29, 1918, Serial No. 225,403. Divided and this application filed April 5, 1919. Serial No. 287,729.

To all whom it may concern:

Be it known that I, CHARLES A. STATLER, a citizen of the United States, residing at Chicago, in the county of Cook and State of Illinois, have invented a certain new and useful Improvement in Roofs, of which the following is a full, clear, concise, and exact description, reference being had to the accompanying drawings, forming a part of this specification.

My invention relates to improvements in roofs and has special reference to roofs constructed of flexible waterproof sheet roofing material commonly made of a wool felt base impregnated with asphaltum or the like.

Among the several objects of my invention are to provide a system of roofing which shall result in producing a better and tighter roof of the class mentioned than has been possible by the methods heretofore in use; which, of, considering its quality, shall cost less, and in which the various sheets composing the roof shall be so sealed together and the metallic fasteners so arranged that no water can seep or leak through to the fasteners.

A further object of my invention is to provide a roof made of flexible roofing material, which shall be highly ornamental in appearance and which shall in general simulate an earthen tile roof.

A further object of my invention is to provide a roof construction, including the use of the roofing material in an elongated strip form, and so secured by metallic fasteners that the fasteners are sealed beneath the roofing material against contact with any water which may fall or collect upon the roof.

A further object of my invention is to provide a roof of flexible material such as ready prepared roofing in sheet form and covered with a grit material embedded in the asphaltum material of which the roofing sheets are partly composed, the roof being so formed that the flowing of water or sliding of snow thereon is impeded sufficiently to materially assist in the preservation of the roof and whereby the grit coating is prevented from being washed off, as occurs with ordinary roofs of this character.

A further object of my invention is to provide a roof of the character defined, hav-

ing ridges or steps and having colored grit embedded on its exposed surface to simulate 55 earthen tile.

A further object of my invention is to provide a roof construction whereby the use of sheet metal in the making of the roof, especially in the construction of gutters and 60 the like, shall be eliminated to the end that the roof shall be more durable and more cheaply constructed than those commonly made.

My invention consists generally in a system 65 for covering a roof with waterproof flexible material in sheet form, to make the roof water tight, and which includes the securing of the top surface of the roofing material down upon the roof boards along 70 one edge and then the turning of the flexible sheets over and upon the secured edge or portion thereof whereby the securing metallic fasteners or nails are effectually covered and sealed from contact with any 75 water which may fall on or collect upon the roof.

My invention also consists in a system, as described, which results in an appearance quite similar to a tile roof but which is wind 80 and weather tight and of much less corresponding weight and cost than a tile roof.

My invention also consists in a roof of the material described having a series of transverse or horizontally disposed baffles, ridges, 85 stops or dams, which impede the flow of water down the roof and serve to prevent snow slides.

My invention also consists in the several features of construction and in the various 90 arrangements and combinations of devices and parts whereby I am enabled to attain the above mentioned and other objects and all as hereinafter described and particularly pointed out in the appended claims. 95

The present application is a division of my copending application filed March 29, 1918, Serial No. 225,403 entitled Roofs, which has matured into Patent No. 1,338,262, April 27, 1920. 100

For a clear understanding of my invention, attention is directed to said accompanying drawings, in which:

Figure 1 is a fragmentary perspective view of a roof constructed in accordance 105 with my invention;

Fig. 2 is a vertical transverse sectional view of the roof on the line 2—2 of Fig. 1;

Fig. 3 is a fragmentary section similar to Fig. 2 and illustrating the method of laying the sheets or strips composing the finished roof;

Fig. 4 is a fragmentary horizontal section of the roof on the line 4—4 of Fig. 1;

Fig. 5 is a fragmentary horizontal section 10 of the roof on the line 5—5 of Fig. 1;

Fig. 6 is an enlarged fragmentary detail section on the line 6—6 of Fig. 1, and similar to Fig. 4;

Fig. 7 is a perspective view of one of the 15 ridge covering members;

Fig. 8 is an enlarged vertical fragmentary section on the line 8—8 of Fig. 1; and

Fig. 9 is a fragmentary section of the preferred form of flexible roofing material.

Roofs, as usually and commonly constructed of the flexible roofing material, are made of sheets of various sizes laid and secured in overlapping relation and providing substantially flat roofs, or in other words, 25 roofs having no ridges, projections, or ornamentation, except possibly printed or colored substantially flat figures or lines formed on the roofing material.

So far as I am aware no method of laying 30 this ready-to-lay flexible roofing material has so far been devised whereby the metallic fasteners such as nails are sealed beneath the roofing material against contact with water which may fall on or collect 35 upon the roof. Usually the securing nails are driven down into the roof through the overlapping edges of the sheets and their heads are exposed to the weather, except for a possible coating of asphalt paint or the 40 like. In a few instances the nails or fasteners have been covered over by portions of the flexible material but not in a manner to seal the fasteners and the roof against the entrance or seepage of water through 45 openings left in the flexible material, of which the roof is composed.

As shown in Fig. 1, I build the main part 50 of the roof of elongated sheets or strips 1 of the flexible material, 2 is the ridge of the roof, 3 is the lower edge or eave, 4 is the gable end and 5 is the hip-roll.

In constructing or laying the roof I first prefer to provide a vertical edge board 6 for the eave to form with the roof 7 itself 55 a space for the gutter, and in beginning the laying of the roofing material I first take a strip 8 of the roofing material and secure one edge of it to the upper edge of the board 6 by means of a clamping strip or bar 9 60 which may have the form of a round rod as shown in Figs. 2 and 3. I secure this rod and the sheet 8 by nails 10 which I drive down through the rod the edge of the sheet and into the upper edge of the board 6. I 65 then turn the sheet 8 over the rod 9 and

form it down into the angle between the edgeboard 6 and the roof to form the gutter 11. In thus turning the sheet 8 over I cover the nails 10 and the clamping rod 9. For temporarily holding the upper edge of the 70 sheet 8 after it has been turned over upon the roof, I secure it in position by nails 12.

Having thus formed the gutter, I proceed to the construction of the roof itself, and this I do in the manner best illustrated 75 in Fig. 3, the upper edge of the first sheet having been secured as heretofore explained. I next arrange a second sheet 13 upon the first sheet and with its weather face in contact therewith, as shown in dotted lines Fig. 80 3, its upper edge 14 parallel and coincident with the upper edge of the sheet already laid, and I secure the upper edge 14 of the second sheet in position by means of a strip of wood 15 which I nail upon the roof and 85 upon the upper overlapped edges of the two sheets by means of nails 16, and whereby the edge 14 of the second sheet and the upper edge of the lower sheet are firmly clamped together and held in position upon 90 the roof. It will be understood that the two weather surfaces of the two sheets are in contact beneath the strip 15 and that the grit with which they are coated serves to hold them against any possible relative 95 movement. Furthermore, the pressure caused by the nailing of the strip 15 upon the roof and the heating of the roof by the sun finally causes the asphaltic material of which the sheets are partly composed to 100 soften and effectually seal the strips together along their secured edges below the clamping strip 15.

Having secured the edge of the second sheet upon the upper edge of the first sheet 105 as described, I next turn the second sheet up upon the roof over the strip 15, thereby covering the strip 15 and the nails 16, and proceed with further strips until I reach the ridge.

The sheets 1 are thus secured along their 110 horizontal edges and are sealed together by means of the strips 15 and nails 16 and the amalgamating of the materials of which the sheets are made so that the final product is a water tight roof having no openings 115 through which water can seep or leak, even if the water stands upon the roof to some appreciable depth. Furthermore, the use of the strips 15 and the turning of the flexible material over these strips provides a roof 120 having steps 17 of appreciable depth and the depth of the steps 17 can be made to simulate the edges of earthen tiles which are usually about one-half to three-quarters 125 of an inch in depth at their lower edges, and I preferably use a grit coating on the roofing material in color similar to the color of tiles which it is desired to simulate.

A very valuable feature of my invention 130

resides in the fact that the construction lends itself particularly to the covering of old shingle roofs because the strip 15 can be nailed securely in place above or upon the old shingles, pressing and holding them down tight, and the clamping strip provides a solid, firm and substantially rigid foundation for the roofing sheets which avoids the water catching hollows produced by nailing the sheets directly to the roof and particularly when the sheets are secured on top of old shingles. Furthermore the space 18 beneath the roofing strips 1 leaves ample room for the old shingles without the detrimental feature of the forms of the old shingles showing through the finished roof. This particularly results from the fact that I make the strips 1 relatively narrow, to simulate tiles which are usually eight or nine inches in length, and consequently the weight of the strips 1 is not sufficient to cause them to conform with the shapes of the shingles even if the roofing material becomes softened in summer by the sun.

In covering the two sides of the roof I run the upper edges of the last sheets up upon the ridge member 19, Fig. 2, and then I proceed to cover the ridge member 19 as follows: I take a long strip of the roofing material 20 and lay it upon the roof with one edge adjacent to the ridge pole 19 and secure it in position by means of a wooden strip 21 and nails 22. I then secure a second wood strip 23 along the other edge of the roofing strip 21 with nails 24 and form the roofing strip 21 around upon and over the nails 24, as shown in Fig. 2, driving the nails 24 down into the roof on the opposite side of the ridge pole. The nails 22 and 24 are thus completely inclosed and protected against any moisture or water.

Another important feature of my improved roof is that the sheet 1, due to the softening influence of the sun will settle down between the clamping strips 15, as shown in dotted lines Fig. 3, the clamping strips 15 and the lower edges of the roofing sheets 1, which are wrapped around same, forming ripples, baffles or dams on the roof which effectually prevent snow slides, or the rushing of the rain water down the roof at a speed to loosen or carry away the grit material with which I preferably cover the sheets 1.

Preferably, as illustrated in Fig. 1, I make the flexible roofing strip 1 long enough to extend the whole length of the part of the roof which I am covering, so as to avoid, as far as practicable, any vertically extending joint at the end of the strip between the vertically extending projections 25. For the purpose of sealing the roof against the entrance of water at the ends of the strips 1, I form the ends of the strips 1 upwardly, in the form of vertically extending flanges 30,

adapted to contact tightly with the side faces of the projections 25 as best shown in Fig. 4. These flanges 30 may obviously be nailed or otherwise secured to the side faces of the projections 25, but whether they are thus secured or not, they are held tightly pressed against the projections 25 by the U-shaped covering members 27 when these members are sprung down over the ridges 25 and over the adjacent upturned flanges 30 of the roofing strips 1.

An advantageous feature of this structure is that while I may secure the several U-shaped members 27 upon the projections 25 by nails driven through the smaller ends thereof and which nails are adapted to be covered by the next higher U-shaped member 27. I may omit these nails and yet hold these U-shaped members securely in place, because I make these U-shaped members 27 yielding or springy and I turn the covering within the side edges thereof. In consequence of this the grit covered or inner surface of the covering within the U-shaped members 27 contacts directly with the grit covered surface of the flanges 30, and when these members 27 have once been forced down into place upon the projections 25, these two contacting grit surfaces interlock so tightly together that it is difficult to remove the members 27. This locking of the members 27 in position eliminates any possibility of the wind lifting or loosening these members 27.

When the sheet 1 ends at the gable edge of the roof, I preferably cut the strip 15 a trifle short of the end of the roof, as best shown in Fig. 5, so that I can flatten down the overlying layers of roofing adjacent to the end of the roof, and then I seal the ends of the several sheets 1 tightly to the roof by means of a strip of wood 31 which I nail vertically on the roof, substantially flush with the end of the roof. While the nailing on of the strip 31 might be sufficient to seal the ends of the strips 1 to the roof, I prefer to cover the strip 31 with the roofing material, and thus not only protect the strip 31 from the weather, but also protect the nails with which the parts are secured, and also thoroughly seal the joint between the roofing strips 1 and the roof base. For this purpose I prepare the strip 31 by securing pieces 32 of the flexible roofing material to the under side of the strip 31. After the strip 31 has been nailed in place, I wrap the pieces 32 around the strip 31 and carry them down on the outer end of the roof, securing them against the end of the roof by nails 33 and strips 34 covered over by the strips 32 as best shown in Fig. 5, similar to the manner of securing the strips 20 to the roof around the ridge 19.

In Fig. 8 I have shown an enlarged cross section of the clamping strip 15. While it

is possible to use other shapes of strips I prefer to use strips having the edge 33 around which the roofing strips 1 are formed, slightly rounded as shown so as to best permit the forming of the sheet 1 without fracture. Also I prefer to make these strips slightly wedge shaped, the upper edge 15', being thinner than the lower edge so as to best conform with the roofing strips 1

10 after they have settled down upon the roof. In Fig. 9 I have shown a section of the flexible roofing material which I prefer to use in practising my invention. The base or foundation of the roofing is a sheet of 15' wool felt or some similar fibrous material 35. This is impregnated with a waterproofing material such as asphaltum, and the lower surface may be covered with a paper sheet 36 to prevent the roofing sticking together when rolled up for shipping. The top or weather surface is usually provided with a layer 37 of the asphaltum in which is embedded and secured a coating or covering 38 of grit, sand or gravel. This grit coating 25 may be made of any color to suit the conditions.

It will be understood that the roofing material, as prepared for this purpose, is sufficiently flexible to permit the forming of the sheets around the clamping strips without destroying the waterproof quality of the sheets at these points.

It will now be clear that by means of my invention I am enabled to produce a roof, 35 made out of the flexible roofing material, in which no nails or other metallic fasteners are exposed to the weather or through which water can seep or leak even when the water collects to an appreciable depth upon the 40 roof.

Also that I am enabled, by means of the novel manner in which I secure these sheets upon the roof, to simulate a roof constructed of earthen tile, and furthermore that such 45 construction provides a roof having horizontal baffles, ridges, stops, or dams, which serve to prevent the rushing of water down the roof or the sliding of snow down the roof, both of which are more or less destructive to the roof, and that the washing off of the grit from the roof by the water flowing down or snow and ice sliding is thus substantially completely eliminated.

As many modifications of my invention 55 will readily suggest themselves to one skilled in the art, I do not limit or confine my invention to the specific details of construction herein described.

I claim:

60 1. A roof covering composed of elongated strips of sheet roofing material, arranged substantially parallel with each other, their adjacent edges sealed together, the part of the roof covered by the sheets defined at its

ends by vertically extending narrow projections, the end of the roofing strips bent upwardly against the sides of said vertically extending projections, and U-shaped members embracing said projections and clamping the bent up ends of the strips thereto, thereby sealing the ends of the roofing strips to and upon the roof.

2. The improvement herein described, comprising a part of a roof defined at its ends by vertically extending projections, 65 flexible roofing sheets on the roof extending horizontally from projection to projection and having their ends formed into vertical flanges contacting with the sides of said projections, the horizontal edges of the sheets 70 overlapped and sealed together, and U-shaped covering members embracing said projections and the flanges at the ends of the sheets and sealing the ends of the sheets to the roof.

3. In a roof of the kind described, flexible roofing sheets having grit covered weather surfaces extending horizontally over the part of the roof covered thereby, the adjacent edges of the several sheets sealed together, 80 vertically extending projections defining the ends of the part of the roof covered by said sheets, the ends of the sheets formed upwardly in contact with the adjacent faces of said projections, and U-shaped covering 85 members having yielding side walls embracing said projections and the upturned ends of the roofing sheets, said U-shaped members having grit covered surfaces extending within same, and adapted to contact with the 90 grit surfaces of the upturned ends of said roofing sheets, and whereby said covering members are held against removal.

4. In a roof covering composed of a plurality of elongated strips of flexible sheet 105 roofing material, the adjacent edges of the strips overlapped and the edge of the top sheet in each instance turned under, a thickening strip within the turned under edge, said strip being thicker at one edge than at 110 the other and arranged with the thicker edge embraced by the turned under edge of the top sheet.

5. A roof covering composed of a plurality of elongated strips of flexible sheet roofing 115 material, the adjacent edges of the strips overlapped and the edge of the top sheet turned under in each instance a thickening strip within the turned under edge said strip being thicker at one edge than at the other 120 and arranged with its thicker edge embraced by the turned under edge of the top sheet and said thicker edge being rounded in contour so that no sharp edge is presented to the embracing roofing sheet.

In witness whereof I hereunto subscribe my name this 2nd day of April, 1919.

CHARLES A. STATLER.
